UNITED STATES PATENT OFFICE.

TEUNIS JOHANNES MARINUS REYNDEERS, OF ROTTERDAM, NETHERLANDS.

FOUNTAIN DRAWING-PEN.

1,214,072.

Specification of Letters Patent. Patented Jan. 30, 1917.

Application filed December 5, 1913. Serial No. 135,181.

To all whom it may concern:

Be it known that I, TEUNIS JOHANNES MARINUS REYNDEERS, citizen of the Netherlands, residing at Rotterdam, the Netherlands, have invented certain new and useful Improvements in Fountain Drawing-Pens, of which the following is a specification.

There is already in existence a fountain-drawing-pen, in which the ink flows by gravity from the reservoir between the legs of the drawing-pen. In this case the space between the legs is connected with the ink-reservoir by a little tube, the disadvantage of this construction is, that the ink will either not flow through this narrow tube, or that, at the end of the tube, a drop will be formed, which if it falls may cause a blot. By the present invention I eliminate this disadvantage by adjusting the legs of the fountain-drawing-pen closely to the hole through which the ink leaves the reservoir, and by moving the legs up and down in such a way that, with the exception of the nibs, they remain within the reservoir.

The invention is illustrated in the accompanying drawing, in which:

Figure 1 is a front-elevational view of the fountain-drawing-pen. Fig. 2 is a vertical section, the legs appearing in side elevation. Fig. 3 is a vertical section through the front end of the pen, one of the legs appearing in front-view. Fig. 4 is a side-view of the legs, in extended position. Fig. 5 is a sectional side elevation of a modified form of the invention.

l, l are the legs of the drawing-pen which at the top are joined by a yoke *d* in such way as to take, if not pressed together, the position indicated by Fig. 4; but it will be understood that the spacing of the legs may vary with the thickness and elasticity of the material.

hh are adhesion plates, fixed between the legs, for instance by a pin or in any other suitable way.

a is the reservoir inclosing the drawing-pen's legs (the nibs excepted), and the front end of the pen may be shaped to correspond with the legs, or may end in a flange formed in such a way as not to allow the ink to run out between this flange and the legs.

The mouth which presents a substantially conical form, or its point, is preferably not fastened to the reservoir (as shown in Fig. 5) and may be attached by pushing or screwing. In the case of screwing, the legs may previously be drawn upward into the tube, (to prevent their being damaged). After the mouth has been removed, they may be brought into their former position and cleaned thoroughly.

The yoke *d* is connected with a bar *b* engaging a mechanism in the head, which enables the legs to be adjusted upwardly or downwardly in the middle of the apparatus. This might be done by making the bar *b* end in a screw *e* turning in a cap or sleeve *m*. This sleeve *m* turns partly in and partly on the reservoir *a*, motion in the vertical direction being made impossible by the pin *f* which projects in a round hole of the sleeve *m*. *i* is a band, for instance of india rubber or cork, to prevent loss of ink.

By turning the end *n*, of the sleeve *m*, the legs of the drawing-pen are screwed up and down and the nibs come into the desired position. The front end *k* of the reservoir has such dimensions that the upper reservoir is always in open connection with the space between the legs. The reservoir may be filled with ink by screwing up the legs, by doing which the whole mouth is made free to be filled.

A considerable advantage of this invention is that the ink, only a very small part of which is exposed to the influence of the air, flows much longer than in other drawing-pens, and does not dry up and obstruct the regular function of the pen. Moreover the pen, if not used, is closed hermetically by a cap *g*.

Having now particularly described and ascertained the nature of my said invention, and in what manner the same is to be performed, I declare that what I claim is:

A pen comprising a casing forming a reservoir, one end of said casing being reduced in diameter, an internally threaded sleeve revolvably mounted in the end of the casing which is of full diameter, a rod within said casing having one of its ends threaded and adapted to engage said inter-

nally threaded sleeve, a yoke at the other end of said rod, pen points carried by said yoke and adapted to project through the reduced end of the casing, and means between said pen points for slowly feeding ink thereto from said casing.

Dated the 8 day of Nov., 1916.

In testimony whereof I affix my signature in presence of two witnesses.

TEUNIS JOHANNES MARINUS REYNDEES.
